ELECTROTHERAPY FACIAL APPLICATOR

Mary R. Christopher, 7005 DeVille Drive,
Fort Worth, Tex. 76118

Filed June 19, 1967, Ser. No. 7,506

Term of patent 14 years

(Cl. D83—1)

Fig. 1

Fig. 2

Fig. 3

Fig. 4

FIG. 1 is a perspective view of an electrotherapy facial applicator embodying my new design;

FIG. 2 is a right side elevational view of the applicator shown in FIG. 1;

FIG. 3 is a left side elevational view of the applicator shown in FIG. 1; and

FIG. 4 is a front elevational view of the applicator of FIG. 1.

I claim:

The ornamental design for the electrotherapy facial applicator, as shown.
